EDUARD EGLI AND EDWIN SCHOCH, OF RUTI, SWITZERLAND, ASSIGNEES TO MASCHINENFABRIK RÜTI VORMALS CASPAR HONEGGER, OF RUTI, SWITZERLAND

SHUTTLE-GUARD FOR LOOMS

Application filed November 18, 1929, Serial No. 408,109, and in Switzerland November 30, 1928.

The present invention relates to shuttle stop motions for fixed reed and loose reed looms of every kind in which, when a shuttle has irregularly entered the shuttle-box, an abutment, on the movement of the lathe towards the beam, effects the disconnection and stopping of the loom.

With a known shuttle stop motion of this kind every time the shuttle enters correctly and every time the lathe is started a pusher is actuated, which with looms running at high speed can easily cause disturbances. Also with this known motion an opening is necessary in front of the shuttle-box, so that the shuttle may not bear upon the entire length of the edge of the box and thus may not be too quickly worn out.

In order to avoid these disadvantages the improved shuttle stop motion comprises a shaft rotatably supported in bearings, two vertical feeler arms fixed to the said shaft and extending to both sides within the shuttle box in the path of swing of the shuttle when not completely entered, a vertically movable stopping lever in driving connection with the said feeler arms, a vertical push rod pivoted to the stopping lever and having a push knob capable of being aligned with a push knob of the lathe when lowered by one of the feeler arms and by the stopping lever, and a horizontal connection between the push rod and the weft fork lever which connection admits vertical movements of the push rod.

With this motion all the parts are in the position of rest during the regular operation of the loom and any wear of the tongues, abutments, and so forth, is avoided. In the front wall of the shuttle-box no opening is necessary. The shuttle lies thereby upon the entire length of the edge and is subjected to less wear. The shuttle stop motion is arranged on both sides of the loom.

The accompanying drawings illustrate a constructional example of the subject matter of the invention, in which

Fig. 1 shows the device in side view as prepared for operation, with shuttle entered entirely in the shuttle-box in the foremost position of the lathe;

Fig. 2 is a view similar to Fig. 1 showing

the parts when the shuttle is not completely entered, and

Fig. 3 is a plan showing the lathe and position of the shuttle as in Fig. 2.

Referring to the drawings, 1 is a partially illustrated main supporting member of a loom, 2 is the breast-beam with an abutment 3 for the stopping lever 4; 5 is the lathe support in its foremost position, 6 the lathe together with the shuttle box plate 7 and the stopping knob 8 cast thereto; 9 is the front wall of the shuttle box; 10 is the picker in its extreme position; 11a shows the shuttle when it has completely entered the shuttle box; 11b shows the position of the shuttle when it has not fully entered into the box. Upon a shaft 13 extending from one side of the loom to the other and rotatably supported in bearings 12, of which only that one is indicated which is on the work side of the loom, are fixed feeler-arms 14a and 14b extending to both sides within the shuttle-box in the path of swing of the shuttle when not completely entered. Upon the same shaft a lever 15 is rotatably supported on the same side as the loom-stopping apparatus, which lever by means of a spring 16 and an adjustable screw 17 remains in connection with the feeler arm 14a and therefore follows the movements of the latter. Upon a pin 18 of the lever 15 is mounted a push rod 19 having a push knob 20. The push rod 19 is again loosely connected by a guide pin 21 with the usual knock off lever 22 in such a manner that the pin 21 is able to slide in a slot 23. The lever 22 is supported rotatably about a pin 24 upon the breast-beam 2. A tensile spring 25 secured to a fixed point 26 brings the lever 15 against an abutment 27 and thereby secures the entire device in the position ready for working.

The manner of operation of the device described is as follows: If the shuttle 11b does not enter completely into the shuttle box 7, 9 then the former comes to a standstill behind the feeler-arm 14a left side, or 14b right side. The arms 14a, 14b are hereby impelled forward on the forward motion of the lathe 6. This impulse is transmitted over the spring 16 to the lever 15 and hereby effects a downward movement of the push rod 19, or of the 11a

push knob 20 connected therewith. This downward movement is limited by the upper closed end of the slot 23 in such a manner that the push knob 20 comes into line with the stopping knob 8 of the forwardly swinging lathe 6 and hereby is impelled forwardly until the knock off lever 22 connected by the guide pin 21 ejects in a generally known manner the stopping lever 4 from the abutment 3 of the 10 breast-beam 2 and thereby effect the stopping of the loom. The spring 16 takes up the excess movement of the feeler-arms 14a, 14b, and the screw 17 serves for the mutual adjustment of the said feeler-arms 14a, 14b and 15 of the stopping lever 15. The spring 16, after the stopping of the loom, brings the device again to the abutment 27 in the correct position for starting working, in which position, when the shuttle 11a has completely 20 entered into the shuttle-box, the stopping knob 8 of the lathe does not engage the push knob 20 of the push rod 19.

What we claim is:

1. A device of the kind described, comprising a shaft rotatably supported in bearings and extending from side to side of the loom, two vertical feeler arms fixed to the said shaft and extending to both sides within the shuttle box in the path of swing of the shuttle when not completely entered, a vertically movable lever in driving connection with the said feeler arms, a vertical push rod pivoted to the said lever and having a push knob capable of being aligned with a push knob of the lathe when lowered by one of the feeler arms and by the said lever, and a horizontal connection between the push rod and the weft fork lever which connection admits vertical movements of the push rod.
2. A device of the kind described comprising a through-going shaft rotatably supported in bearings, two vertical feeler arms fixed to the said shaft and extending to both sides within the shuttle-box in the path of swing of the shuttle when not completely entered, a vertically movable lever rotatably supported upon the said shaft and connected with one of the feeler arms by a spring and an adjustable screw, a vertical push rod pivoted to the said lever and having a push knob capable of being aligned with a push knob of the lathe when lowered by one of the feeler arms and by the said lever, and a horizontal connection between the push rod and the weft fork lever which connection admits vertical movements of the push rod.

In testimony whereof we have affixed our signatures.

EDUARD EGLI.
EDWIN SCHOCH.
